UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

WORK-CLAMP-POSITIONING DEVICE.

Application filed December 29, 1922. Serial No. 609,575.

To all whom it may concern:

Be it known that I, EDWARD B. ALLEN, a citizen of the United States, residing at Newtown, in the county of Fairfield and State of Connecticut, have invented certain new and useful Improvements in Work-Clamp-Positioning Devices, of which the following is a specification, reference being had therein to the accompanying drawings.

10 This invention relates to buttonhole sewing machines of the type having stitch-forming mechanism and a work-clamp with means for relatively moving them to sew around a buttonhole. Some machines of this type employ a buttonhole cutter which is operated to cut the buttonhole prior to sewing, in which case means are usually provided for spreading the work-clamp to open up the buttonhole-slit for passage of the needle making the overedge stitch. In other machines, the work-clamp is operated to spread the work prior to sewing but the buttonhole cutter is operated to cut the buttonhole after the sewing operation. It will be appreciated that, in all buttonhole sewing machines wherein sewing and slit-cutting mechanisms operate at different times upon the work, nice registering of the work-clamp with the sewing and cutting mechanisms is essential to the production of acceptable work.

Heretofore, the feed-cam connections for moving the work-clamp have usually been depended upon to hold the work-clamp in position during the action of the buttonhole cutting and clamp-spreading mechanisms, and it has been found that imperfect work is sometimes produced because of the inaccurate registering of the work-clamp and the buttonhole-cutter. It has also been noticed that, when handling heavy work, there is a tendency for the clamp-spreading devices to displace or distort the work-clamp mechanism.

45 The present invention has for an object to provide a buttonhole sewing machine with means for insuring that the work-clamp and buttonhole cutter will be in register when the buttonhole is cut.

50 Another object of the invention is to overcome the tendency of the work-clamp mechanism to become displaced or distorted in the spreading operation on heavy work.

Further objects of the invention will appear from the following description and claims.

To the accomplishment of the ends in view, there is provided mechanism, in addition to the usual feeding means, for registering the work-clamp and buttonhole cutter during the buttonhole cutting operation. The novel means herein provided is preferably constructed in the form of an interlocking connection between the work-clamp and the buttonhole-cutter for relatively fixing or registering these parts during the buttonhole cutting operation. The interlocking connection is preferably afforded by providing the work-clamp carrier-plate with a slot restricted in width to closely fit a movable element of the buttonhole-cutter such, for example, as the usual travelling buttonhole-cutter fulcrum-block. When the buttonhole-cutter is moved to cut the buttonhole, the fulcrum-block, functioning as the bolt of a lock, enters the slot in the clamp-carrier plate and registers the buttonhole-cutter and work-clamp; at the same time locking the work-clamp against sidewise movement. When the buttonhole-cutter is retracted, the fulcrum-block is withdrawn from the slot in the clamp-carrier plate and the latter is unlocked for the usual feeding movements. In the present machine the clamp-spreading mechanism is preferably timed to operate while the cutter fulcrum-block is in the slot of the clamp-carrier plate and the latter is thereby greatly stiffened and prevented from being shifted or sprung laterally under reactionary strains produced by the operation of the clamp-spreading mechanism; these strains being usually more severe when operating upon heavy work.

In the accompanying drawings Fig. 1 is a horizontal section through the bracket-arm standard of a buttonhole sewing machine embodying the invention, showing the work-clamp and machine bed in plan. Fig. 2 is a fragmentary plan view of the machine bed with the rearward portions of the separable work-clamping elements broken away. Fig. 3 is a fragmentary side elevation of the buttonhole cutting mechanism, clamp spreading mechanism and the certain elements of work-clamping mechanism.

Fig. 4 is a fragmentary plan view of the machine bed showing the longitudinal slide frame and the cross-slide-plate which carries the work-clamping elements or plates; the latter having been removed. Fig. 5 is a plan view of the clamp-spreading toggle mechanism and its carrier-plate. Fig. 6 is a side elevation of the buttonhole cutting mechanism. Fig. 7 is a section on the line 7—7, 10 Fig. 5. Fig. 8 is a fragmentary transverse vertical section through the machine bed and work-clamp, showing the buttonhole cutter in end elevation. Fig. 9 is a fragmentary bottom plan view of the cross-slide-plate which carries the separable work-clamping members. Fig. 10 is an elevation of the toggle mechanism shown in Fig. 5. Fig. 11 is an enlarged plan view of the wear-lugs which are attached to the cross-slide-plate element of the work-clamp mechanism, 20 and Fig. 12 is a rear elevation of one of the work-clamp-lever fulcrum-blocks.

In the preferred embodiment of the invention, as illustrated, 1 represents the bed 25 and 2 the bracket-arm standard of a button-hole sewing machine such as disclosed in my copending application Serial No. 537,381, filed Feb. 18, 1922. This machine embodies the usual stitch-forming mechanism represented by the needle 3, Fig. 3, and needle-throat 4, operating at a fixed location relative to the bed 1.

The work-clamp of the particular machine illustrated is movably mounted on the bed 1 and comprises the usual laterally separable lower work-supporting plates 5, 5, and upper clamping feet 6, 6 pivotally carried at the forward ends of the clamping levers 7, 7 which at their rearward ends are 30 fulcrumed between the parallel upstanding plates 8, 8, Fig. 8, of the clamp-lever fulcrum blocks 9, 9 mounted respectively on the separable work-supporting plates 5, 5. When the machine is started, the clamps are 35 closed by the downward movement of a clamp-closing lever 10, Fig. 1, having a roller 11 at its free end which depresses an arm 12 fixed to one of the separably connected rock-shaft sections 13, 13 journaled at the 40 forward ends of the plates 8, 8 of the clamp-lever fulcrum blocks. The rock-shaft sections 13, 13 carry cams 14, 14 which depress the clamp-levers 7, 7 to work-clamping position, Fig. 3.

The fulcrum-supports for the upper clamping levers 7 each comprise a block 7^a, Fig. 12, fulcrumed between the upstanding plates 8 by means of fulcrum screw-studs 7^b. Fixed vertically in the block 7^a and extending above the latter is the screw-pin 7^c carrying the thumb-nut 7^d. The thumb-nut 7^d has an upper flange 7^e, and lower flange 7^f connected by a reduced neck 7^g which passes through the slot 7^h extending longitudinally of the clamping lever 7 at the rear

end of the latter. A plate 7ⁱ is superposed upon the lever and has a slot 7^j cut transversely through one edge of said plate 7ⁱ to admit the neck 7^g of the thumb-nut 7^d. The plate 7ⁱ is formed with a longitudinal slot 7^k 70 through which passes a screw 7^m threaded into the lever 7. By turning the thumb-nuts 7^d, the work-clamp levers 7 may be quickly adjusted to accommodate work of any thickness and by loosening the screws 7^m the levers 7 may be adjusted longitudinally of their fulcras 7^b to longitudinally register the clamping feet 6 and plates 5, after which the screws 7^m are tightened.

The separable work-clamping plates are superposed upon and carried by the cross-slide-plate 15, the rearward half of which slidably rests upon the bed 1, as shown in Figs. 2, 4 and 8. The cross-slide-plate 15 is formed at its front end with depending lugs 16, 16 which are apertured to slidably fit upon the cross-slide-rod 17, connecting the front ends of the side members 18, 18 of the longitudinal slide-frame A; the rearward ends of the members 18, 18 being connected by means of the plate 19. By referring to Figs. 4 and 8 it will be noted that the side members 18 are fitted to the undercut guideways 20, 20 extending longitudinally of the bed 1.

The separable work-clamping members are provided at their forward ends with flattened depending pins 21, 21, Figs. 1 and 9, which are detachably received in the open-sided apertures 22, 22 at the front ends of the forward clamp-spreading levers 23, 23 pivotally mounted at 24, 24 on the under side of the cross-slide-plate 15. Clamp-spreading movements are imparted to the levers 23 by means of the link 25 which extends between the levers 23 and is formed with wedge surfaces 26 coating with follower-blocks 27 secured to the levers 23 and adjustable crosswise of the latter by means of screw and slot connections 28. A spring 29 anchored at its opposite ends to pins 30 on the respective levers 23, holds the latter in contact with the link 25. The link 25 derives its clamp-spreading and unspredding motions from the mechanism which spreads the rearward ends of the separable work-clamping members and which will now be described.

Slidably resting upon the plate 19 of the longitudinal slide-frame A and screwed to the cross-slide-plate 15 at 31, 31 by screws 32, 32 is the toggle plate 33 having transverse guideways 34, Fig. 5, for the slide-blocks 35. Pivoted centrally of the plate 33 is the lever 36 which is connected at its opposite ends by pivot pins 37, 38 to the links 39, 40, the latter being pivotally connected to the slide-blocks 35. The lever 36 and links 39, 40 constitute a toggle device which, when straightened, imparts outward or 120

clamp-spreading movements to the slide-blocks 35. The blocks 35 carry upstanding pins 41 which impart the clamp-spreading movements of the blocks 35 to abutment screws 42, 42, Fig. 1, carried respectively by the outer side members 8 of the clamp-lever fulcrum-blocks 9 mounted on the separable lower clamp-plates 5. The pivot pin 37 has a downward extension 43, Fig. 7, which enters the apertured rear end of the link 25, thus connecting the clamp-spreading levers 23 and slide-blocks 35 for simultaneous clamp-spreading movements. The parts are preferably so adjusted that these movements are of equal amplitude, whereby the clamp-plates are spread equal distances at their opposite ends.

One of the slide-blocks 35 has pivotally mounted thereon at 44 the lever 45 having a forked extremity 46 embracing the pivot pin 37. It will be clear that when the outer end of the lever 45 is moved forwardly or to the left, Fig. 1, the clamp-plates 5 will be spread, and vice versa.

The clamp-spreading mechanism is actuated from a cam 47 on the well known cutter-shaft 48 which at an appropriate time is driven for one revolution only through the usual one-rotation clutch-connection 49 with the continuously running cutter-actuating pulley 50. The cam 47, Fig. 3, swings the T lever 51 about its fulcrum (not shown) at the bottom of its upright leg and causes its forwardly extending arm 52 to push the lever 45 to clamp-spreading position.

The means for relatively moving the stitch-forming mechanism and work-clamp to sew around a buttonhole preferably comprises the usual feed-wheel 53 having in its upper face the longitudinal feed-groove 54 and lateral feed-groove 55. The longitudinal feed-groove 54 is entered by the follower 56 on the lever 57 fulcrumed at 58 on the bed 1 and connected by the link 59 to the longitudinal slide-frame A. The lateral feed-groove 55 is entered by the follower 60 carried by the lever 61 which is coupled at 62 to the rearward arm 63 of a lever fulcrumed at 64 on the bed 1; the forward arm 65 of said lever having a sliding connection 66 with the slideway 67 carried on the under side of the cross-slide-plate 15.

The buttonhole cutting mechanism preferably comprises the cutter-levers 68, 69 which are fulcrumed at 70 on the travelling fulcrum block 71 slidable longitudinally of the bed 1 in ways 72, Fig. 8, formed in the said bed. The cutter-levers are given their closing movements by means of the usual cutter-closing cams 73, 74 on the cutter-shaft 48. The cutter-advancing and -retracting movements are derived from a cam 75 which is fixed on the cutter-shaft 48 and

operates through a follower link 76 connected to a rearward extension 77 of the cutter-lever fulcrum block 71.

The constructive features of the machine above described, as well as associated features not herein specifically referred to, are substantially in accordance with the disclosure of my said copending application and my Patent No. 15,324, reissued April 4, 1922, to which reference may be had for a more complete description of the machine.

With the foregoing as a basis the constructive features of the present improvement, in its preferred embodiment, will now be set forth.

Heretofore, in most cases, the feed-cam and its lateral feed connections have been depended upon to laterally fix the work-clamp in buttonhole cutting position. Wear in these connections will in time result in lost motion and in inaccurate positioning of the work-clamp for the cutter. I now preferably provide a direct interlocking connection between the work-clamp and button-hole cutter to insure that these parts will be in register when the buttonhole is cut. So far as I am aware, this interlocking connection is broadly new in a buttonhole sewing machine.

In my prior constructions the cross-slide-plate of the work-clamp was commonly provided with a longitudinally extending clearance slot for the cutter-lever fulcrum-block. This slot was, throughout its length, broader than said fulcrum block and the side walls of such slot did not engage the cutter fulcrum block at any time in the cycle of operations. When the buttonhole cutting mechanism was operated the lateral-feed connections with the feed-wheel were depended upon to laterally locate the work-clamp in cutting position.

In the embodiment of the invention illustrated, means are provided for reducing the width of a portion of the cutter-clearance slot in the cross-slide-plate so that the side walls of such slot will be engaged by the cutter fulcrum-block when the latter is advanced to cutting position. This result may be attained, for example, by mounting hardened wear plates 78 on the opposite side faces of the cutter-lever fulcrum-block for cooperation with the hardened wear lugs 79 secured to the cross-slide-plate 15. The wear lugs 79 reduce the width of a portion of the slot in the cross-slide-plate 15 and have beveled corners 80 to relatively guide the fulcrum-block 71 and cross-slide-plate 15 into interlocking relation; the fulcrum-block 71 operating as the bolt of a lock.

When the machine is to be operated the operator presses the usual starting button which trips the clamp-closing mechanism into operation. After the clamps are closed the clamp-closing mechanism trips the one-

rotation clutch device 49 and effects the coupling of the cutter shaft 48 to the continuously rotating pulley 50 for one revolution during which the cutter-levers are advanced from their retracted or inoperative position, Fig. 4, to cutting position, Fig. 2. The advance of the cutter-levers carries the wear-plates 78 forwardly into engagement with the wear-lugs 79 and locks the cross-slide-plate in a fixed lateral position relative to the buttonhole cutting mechanism and the machine frame. After the buttonhole has been cut and while the cutter-levers are being retracted, the cam 47, Fig. 3, acts through the lever 51 to spread the work-clamp. Fig. 3 illustrates the relative positions of the parts when the clamp-spreading lever 51 occupies its extreme forward position, i. e., when the clamps are fully spread, and it will be seen that the rearwardly moving wear-plates 78 are still in engagement with the wear-lugs 79 and prevent side twisting or shifting of the cross-slide-plate 15 under the reactionary strains produced by the forward pressure of the lever 51 upon the lever 45 of the clamp-spreading toggle mechanism. Except for the interlocking connection herein provided, there would be a tendency for the cross-slide-plate 15 to spring sideways about its front end supporting means 16, 17 as a fulcrum, under the reactionary strains produced by the clamp-spreading lever 51. These strains acting through the cross-slide-plate 15 would also tend to distort the longitudinal slide frame 18, 17, 18, 19 from rectangular to rhomboidal form. By the use of the present interlocking connection the distortion of the cross-slide-plate 15 and longitudinal slide frame 18, 17, 18, 19 is prevented, even under the severe strains encountered when operating on heavy over-coats and the like.

While I have disclosed the invention as embodied in a buttonhole sewing machine of the type illustrated in my said prior patent and copending application, it will be recognized by those skilled in the art as being applicable in its broader aspects to buttonhole sewing machines of various types; not being limited to machines in which the relative movement between the stitch-forming mechanism and work-clamp is produced by moving the work-clamp.

Having thus set forth the nature of the invention, what I claim herein is:

1. A buttonhole sewing machine having, in combination, stitch-forming mechanism, a work-clamp, means for relatively moving and positioning the stitch forming mechanism and work-clamp to sew around a buttonhole, a buttonhole cutter, and means for locking the work-clamp and buttonhole cutter against relative lateral displacement during the buttonhole cutting operation.

2. A buttonhole sewing machine having,

in combination, stitch-forming mechanism, a work-clamp, means for relatively moving and positioning the stitch-forming mechanism and work-clamp to sew around a buttonhole, a buttonhole-cutter, and an interlocking connection between the work-clamp and buttonhole cutter for relatively fixing these parts laterally of the button-hole slit during the buttonhole cutting operation.

3. A buttonhole sewing machine having, in combination, a frame, stitch-forming mechanism, a work-clamp, means for moving and positioning the work-clamp relative to the stitch-forming mechanism to sew around a buttonhole, buttonhole cutting mechanism, and means independent of said first-mentioned means, for laterally fixing said work-clamp relative to the machine frame during the operation of the button-hole cutting mechanism.

4. A buttonhole sewing machine having, in combination, a frame, stitch-forming mechanism, a work-clamp, means for relatively moving and positioning the stitch-forming mechanism and work-clamp to sew around a buttonhole, clamp-spreading means, and locking means independent of said first-mentioned means, for laterally fixing said work-clamp relative to the machine frame during the operation of the clamp-spreading mechanism.

5. A buttonhole sewing machine having, in combination, a frame, stitch-forming mechanism, a work-clamp, feeding means for moving the work-clamp to sew around a buttonhole, clamp-spreading mechanism, and means for locking the work-clamp to the machine frame during the operation of the clamp-spreading mechanism and for unlocking the work-clamp for the sewing operation.

6. A buttonhole sewing machine having in combination, stitch-forming mechanism, a work-clamp, means for relatively moving and positioning the stitch-forming mechanism and work-clamp to sew around a buttonhole, buttonhole cutting mechanism, and a slot and bolt connection for relatively locking the work-clamp and buttonhole cutting mechanism during the buttonhole cutting operation.

7. A buttonhole sewing-machine having in combination, stitch-forming mechanism, a work-clamp, means for relatively moving and positioning the stitch-forming mechanism and work-clamp to sew around a buttonhole, buttonhole cutting mechanism, a slot and bolt connection between the work-clamp and buttonhole-cutter, and means for operating said connection before and after the buttonhole is cut to relatively lock the work-clamp and buttonhole cutter during the cutting operation and to unlock them after the buttonhole has been cut.

8. A buttonhole sewing machine having,

in combination, stitch-forming mechanism, a work-clamp having a carrier-plate formed with a longitudinal slot, clamp-moving mechanism, and buttonhole cutting mechanism including a travelling cutter-lever fulcrum-block adapted to fit and enter the slot in the work-clamp when said fulcrum-block is moved to cutting position.

9. A buttonhole sewing machine having, in combination, stitch-forming mechanism, a work-clamp, means for relatively moving and positioning the stitch-forming mecha-

nism and work-clamp to sew around a buttonhole, a buttonhole-cutter, and a buttonhole-cutter and work-clamp interlock comprising interlocking elements which are out of engagement with one another during the sewing, and means for moving them into interlocking relation during the buttonhole cutting operation.

In testimony whereof, I have signed my name to this specification.

EDWARD B. ALLEN.
